ROSIN SAMPLER

Lewis T. Baker, Jacksonville, Fla.

Application March 27, 1936, Serial No. 71,329

5 Claims. (Cl. 220—85)

This invention relates to a means whereby samples of rosin can be removed readily from barrels.

Heretofore it has been the practice to insert into a barrel through a hole therein, a plug having a coil attached to it within which is held a box into which the rosin will flow during the filling of the barrel. The staves of the barrel are generally formed of green lumber. Consequently the moisture therein has been vaporized by the hot rosin and entered the sampler box or cube, where it has mixed with the rosin and discolored it so as to render it unfit as a sample.

Furthermore, as the box or cube has been held close to the metal plug and within the opening in the barrel, the rosin, after hardening in the box or cube, has become very brittle with the result that when it has been removed, the sample frequently is cracked to such an extent that it cannot be used for grading. This objectionable feature is present generally in cold weather when the plug and the parts joined thereto become greatly chilled.

The sampling means heretofore used and employing a coil, has been objectionable also because when removing the same from the barrel the coil frequently has become caught and entangled with the frazzlings at the edge of the wall of the opening so as to make it difficult and at times impossible to remove a useable sample.

An object of the present invention is to provide a sampler which does not have the objectionable features heretofore enumerated but protects the sample from moisture and consequent discoloration, prevents it from becoming brittle and cracked as a result of chilling, and insures easy removal whenever desired and without interference.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

50 In said drawing—

Figure 1 is a section through a portion of a filled barrel showing the present invention in position.

Figure 2 is a front elevation of the structure shown in Figure 1.

Figure 3 is a view partly in elevation and partly in section showing some of the parts of the sampler separated.

Figure 4 is an elevation of the outer end of the coil and its contents.

Figure 5 is an inner end elevation of the coil and its contents.

Referring to the figures by characters of reference, A designates a portion of a wooden barrel provided with a hole B adapted to receive the sampler constituting the present invention.

The sampler includes a metal tube 1 which is fitted snugly in opening B and has its inner end inturned to provide a narrow flange or seat 2. Ears 3 are formed in opposed portions of the tube near its other end.

Removably mounted in the tube 1 is a coiled wire 4 the ends of which are extended across the ends of the space defined by the coil, the two ends being indicated at 5 and 6 respectively. A box or cube 7 formed of sheet metal and having one or more openings 8 is removably seated in the coil and is held pressed back against the inner terminal 6 of the coil by a spacer 9 which can be in the form of a metal strip bent to form a substantially rectangular member which is interposed between cube 7 and the other terminal 5 of the coil. The inner end of the coil is held against or close to flange or seat 2 by a circular plug 10 fitted snugly in the outer end portion of tube 1 and bearing against the adjacent end of coil 4. This plug has openings 11 through which ears 3 can be bent as shown in Figures 1 and 2, thus to hold the parts assembled. An annular flange 12 is formed on the plug and bears against the outer surface of the barrel.

After the sampler has been placed in the barrel, hot rosin C is poured into the barrel and will flow into tube 1 and fill coil 4, a sample of the rosin entering and filling the box or cube 7.

Tube 1 acts as a shield and protects the contents of box or cube 7 from moisture driven out of the barrel staves by the hot rosin. Thus the sample contained in the box will not become discolored. As the box or cube is held back from the plug 10, excessive cold will not be conducted thereto from the plug and consequently the hardened sample in the box will not become brittle and cracked. As the tube extends through opening B it constitutes a guide for the coil and permits it to be pulled out without difficulty. After the sample has been removed, the plug 10 can be replaced in the tube and again fastened by means of ears 3.

What is claimed is:

1. A sampler including a tubular shield open at its ends, one of said ends being insertable into an opening in a barrel for snug engagement therewith, thereby to be supported rigidly within the barrel, a coil removably mounted in the shield and supported and guided thereby, a box in the coil, and a closure for the outer end of the shield.
2. A sampler including a tubular shield having an open outer and inner end, said outer end being proportioned for snug seating within an opening in a barrel thereby to be supported rigidly within the barrel, a seat at the inner end of the shield, a closure at the outer end, a coil removably mounted between the seat and closure and supported and guided by the shield, and a box within the coil.
3. A sampler including a tubular shield open at its outer and inner end, said outer end being proportioned for snug seating in an opening in a barrel thereby to support the shield rigidly within the barrel, the inner end of the shield having a seat, a closure at the outer end, a coil removably mounted between the seat and closure, a box within the coil, and a spacing device between the box and that end of the coil nearest the closure.
4. The combination with a rosin barrel having an opening, of a sampler including a tubular

imperforate shield open at its inner and outer ends, said outer end being fitted snugly within the opening thereby to support the sampler rigidly within the barrel, a closure removably seated in the outer end, means on the shield cooperating with the closure to hold it detachably in position, a coil removably mounted in the shield and having terminals extending thereacross, and a box within the coil and retained by the terminals.

5. A sampler including a tubular imperforate shield open at its inner and outer ends, the outer end of the shield being proportioned to engage snugly within an opening in a rosin containing barrel thereby to support the shield rigidly within the barrel and in position to shed moisture directed onto the shield from the wall of the barrel, said shield having a seat at its inner end, a closure detachably connected to its outer end, a coil separate from the closure and interposed between said closure and the seat, said coil being removable from the shield when the closure is removed, there being terminals on the coil extending thereacross, a box removably mounted in the coil, and spacing means interposed between the box and one terminal for holding the box adjacent to the other terminal.
